UNITED STATES PATENT OFFICE.

EMIL MÜLLER, OF BERLIN, GERMANY.

CENTRAL BUFFER FOR SHORT COUPLINGS OF RAILWAY VEHICLES.

Application filed January 19, 1921. Serial No. 438,351.

To all whom it may concern:

Be it known that I, EMIL MÜLLER, a citizen of the German Empire, residing at Berlin, Germany, have invented certain new and useful Improvements in Central Buffers for Short Couplings of Railway Vehicles, of which the following is a specification.

The subject of the present invention is the construction of a middle or central buffer in conjunction with a coupling for railway vehicles. More particularly it relates to a central buffer for a short coupling in which consequently the end-walls of the vehicles should be brought as closely together as possible.

The new construction is illustrated in the accompanying drawing in

Fig. 1 in vertical section, in

Fig. 2 in plan, and in

Fig. 3 in front-elevation.

The buffer shaft *a* is made fork-like at its forward portion and the two prongs *b* of the fork are joined together at the lower portion of their front ends by an integral web, a buffer plate *c* being secured on the end faces of said prongs and web, and which plate may either be made flat or dome-shaped. The rear portion of the buffer, comprising the shaft *a*, is in a suitable known manner joined to the frame of the vehicle, but according to this invention provided with a longitudinal bore for the reception of the draw-bar *d*, connected in the known manner with the vehicle frame and which at its forward end carries the draw-hook *e* or the eye *f*. Draw-hook *e* and eye *f* are situated in the longitudinal axis of the

buffer between the fork-like portion *b* of the same. The buffer disk *c* is in its upper part provided with a U-shaped recess reaching downwards beyond the middle, as illustrated in Fig. 3, so that the coupling links *g* (chain links) may from above be inserted into the recess and engaged with the draw-hook *e*. The dimensions between the prongs *b* of the fork of the buffer disk are so chosen that the draw-hook *e* with the coupling links belonging to it have within the buffer sufficient room for the forward and rearward movement of the draw-bar *d*. The disposal of the draw-hook *e* or the draw-eye *f* respectively within the forked buffer shaft enables the employment of the described buffer construction especially for short couplings.

Claim.

A central buffer for short couplings of railway vehicles, comprising a buffer shaft provided at its rear portion with a longitudinal bore, a draw-bar disposed within said bore and provided at its forward end with a coupling member, the front portion of the buffer shaft being fork-shaped and having a web uniting the forked ends at their lower portions, a buffer plate secured to the end faces of the forks and web, said plate having a U-shaped recess, and means adapted to be inserted in said recess for connecting the coupling members disposed between the forks of two adjacent vehicles.

In testimony whereof I affix my signature.

EMIL MÜLLER.

In presence of—

EDUARD PEITZ,
CARL FRIER.
